MACHINE FOR SIZING, TRUING, AND
POLISHING BARS AND TUBES

Walter Siegerist, St. Louis, Mo.

Application October 21, 1935, Serial No. 45,892

7 Claims. (Cl. 80—13)

Bars and tubes in the condition in which they are delivered by the rolling mills are usually so uneven in diameter and so far out of round as to require special treatment to bring them within the customary limits of tolerance. The treatment which has heretofore been the most satisfactory is to draw the cold stock through dies, but it is not practicable for bars of large diameter. However, this cold drawing operation is not suitable for certain steels and other metals and it has certain disadvantages, such as the danger of pulling the stock in two, the intensifying of surface defects and the bending of the stock, and the economic disadvantage that it requires the pickling of the material and requires a separate die for every size of stock. The object of the present invention is to devise a machine which will size, true and polish round bars and tubes and still avoid the above mentioned disadvantages of cold drawing. The invention consists principally in a stand of longitudinally concave work rolls so designed and arranged that they make straight line contact with the work throughout their full operative length. It also consists in the rolls and in the combinations and arrangements of parts hereinafter described and claimed.

In the accompanying drawings in which like reference numerals refer to like parts wherever they occur,

Fig. 1 is a side elevation of a machine embodying my invention;

Fig. 2 is a longitudinal vertical section of the main portion of the machine on a plane between the work rolls and showing the work stock in position;

Fig. 3 is a horizontal section of the work rolls and work stock on the line 3—3 of Fig. 2;

Fig. 4 is a vertical cross section of the work rolls on the line 4—4 of Fig. 3;

Fig. 5 is a detail view of a work roll with the generatrix of its surface indicated thereon;

Fig. 6 is a section of the work roll along the longitudinal axis thereof;

Fig. 7 is a diametral section of the work roll in a plane of the generatrix;

Fig. 8 is a detail view illustrating a yoke in which the work roll is mounted; and

Fig. 9 is a detail sectional view on the line 9—9 of Fig. 8.

The frame work of my machine comprises a base 1 with side walls 2 thereon whose portions are secured together by suitable tie and spacing members 3. In the inner face of each side wall 55 is a recess 4 adapted to form a seat for a stud

or trunnion 5 on a mounting plate 6. To the inner face of this mounting plate 6 is secured as by screws 7, a yoke 8 whose ends 9 are split to receive the necks 10 of work rolls 11 or bearings of said necks. The portion of the stud near the mounting plate is screw threaded and provided with an adjusting nut 12 (see Fig. 9) that bears against the face of the side wall 2 of the frame. The end portion of the stud has an axial bore with an internal thread in which 10 works a screw 13 which extends through a hole in the side wall and whose head is adapted to bear against the outer face of the side wall. The end of the side wall is provided with a threaded hole in register with the recess in which the stud 15 of the mounting plate fits and in this threaded hole is a set screw 14 that is adapted to clamp the mounting plate in adjusting position. By this arrangement, the mounting plate, together with the yoke and the work roll may be adjusted 20 crosswise of the machine.

Each roll yoke is adapted to be tilted to an adjusted position. For this purpose, arcuate slots 15 are cut through the back wall of the yoke and adjusting screws 16 extend through said slots into threaded holes provided therefor in the mounting plate. This arrangement permits the roll yoke to be adjusted and clamped in adjusted position. To facilitate such adjustment, each end of the yoke has a threaded link 17 25 pivotally connected thereto, and extending upwardly through the top portion of the framework. The free ends of the links are threaded and provided with suitable adjusting nuts 18.

The neck 10 of each work roll is connected 30 to a source of power 19 by any suitable connections that will drive the work rolls simultaneously, as, for instance, by the shafting 20 and universal joints 21.

In the construction shown in Fig. 1, there 40 are two work rolls 11 arranged to form a pass. The work rolls are disposed alongside each other with their axes A, B in planes parallel with each other and with the longitudinal axis C of the pass of the mill but the roll axes are tilted in 45 their own planes out of parallelism with the longitudinal axis of the mill, the axis A of one roll being inclined to the same extent but in the opposite direction to that of the axis B of the opposite work roll. Preferably the longitudinal 50 axis of the pass is horizontal and the axes of the work rolls are in vertical planes, and in the present description they are assumed to be in such positions. By reason of their inclination in 55 opposite directions from the horizontal, the work

rolls serve to rotate and feed the work stock W along the longitudinal axis of the pass of the mill at a rate that varies with the angle F of inclination, which angle is hereinafter called the 5 feed angle. Suitable work guides 23 are disposed on opposite sides of the pass in the spaces between the work rolls.

The surface 24 of each work roll is an un-parted hyperboloid otherwise known as a hyperboloid of revolution of one nappe or one sheet of revolution of the type that is generated by a straight line G in a plane parallel to the axis A about which said plane revolves, said line G being inclined to the plane which passes through 10 said axis and is perpendicular to the plane of the line G. The angle of such inclination is hereinafter referred to as the skew angle S of the roll surface. Such surface is concaved endwise and has the characteristic that throughout its 15 circumference all "elements" of its surface, that is, all lines extending lengthwise of its surface at an angle to the plane of its longitudinal axis equal to said skew angle S, are straight lines; and this is true whether the angle is positive 20 or negative. The mathematical formula for the 25 surface of the work roll is

$$\frac{Y^2}{B} + \frac{Z^2}{B} - \frac{X^2}{A} = 1,$$

30 wherein A and B are positive constants and X, Y and Z are the coordinates of points in the surface referred respectively to three axes, each of which intersects the other two at right angles. Fig. 5 is a view of the side of a work roll embodying 35 my invention with the generatrix or element thereof shown by a heavy line on the proximate side of the roll and by a light broken line on the opposite side thereof.

As stated above, the work rolls are disposed 40 with their axes in parallel planes (preferably vertical) and inclined equally and in opposite directions to the axis of the pass of the mill so as to effect longitudinal feeding movement of the work stock W. Such inclination or feed angle F 45 is ordinarily about 15° to 25°. Such feed angle F should ordinarily be equal to the skew angle S of the surface of the work roll. With this arrangement, a horizontal plane passing through the longitudinal horizontal axis of the mill pass 50 will intersect the proximate surfaces of both of the work rolls in straight lines that are parallel with each other and with said longitudinal axis and are elements G of the surface of revolution. Accordingly, the pass of the mill is of even width 55 throughout its length and the work rolls make straight line contact with the work stock throughout the length of the pass.

These facts will be clear upon reference to Fig. 5. This figure shows a side view of a work roll 60 with a hyperboloidal surface conforming to my invention and arranged with its longitudinal axis A horizontal. The line G indicates the straight line generatrix or element whose revolution about the axis A generates the surface of the roll. 65 The angle that the generatrix or line G makes with the horizontal plane of the axis A of the roll is the skew angle S of the roll surface. If, therefore, the longitudinal axis A of the roll is tilted in a vertical plane to an amount equal to 70 the skew angle S, then the straight line or generatrix G becomes horizontal. What is true with respect to one work roll is equally true with respect to the other work roll; that it, when it is tilted to an extent equal to the skew angle of the roll, its straight line generatrix will be hori-

zontal along the surface nearest to the surface of the adjoining roll. In these horizontal positions, the two straight line generatrices are parallel with each other; and they are also parallel with the axis of the pass, because, by assumption, 5 they are in planes parallel with the axis of the pass.

The operation of the mill is as follows: The place of "no slippage" between the surfaces of the two work rolls is at or near the plane of intersection of their axes A, B with a horizontal plane, that is, where the diameters of the surfaces of revolution are least, which place is herein referred to as the circle of the gorge H or pass. The work rolls are accurately adjusted so that the 10 distance between the surfaces of the work rolls at the circle of the gorge H is the same as the diameter desired for the work stock to be put through the machine. The proper spacing apart of the planes of the two rolls axes A, B therefore, always equals the diameter of the circle of the gorge plus the diameter desired for the finished work. 15

Although the lines in which the horizontal plane of the longitudinal axis of the mill intersects the adjacent surfaces of the work rolls are straight lines parallel with said longitudinal axis, the direction in which the pressure is applied to the work changes continuously. On account of the work rolls being inclined with reference to the longitudinal axis of the mill, and consequently the reaction thrust between the rolls at their ends is less than at the circle of the gorge, that is, the roll pressure increases progressively as the bar or stock proceeds through 20 the pass. The maximum pressure is exerted at the "no slippage" point or circle of the gorge H. Consequently, it is easy for the work to enter the pass and after passing the circle of the 25 gorge, the pressure thereon is gradually relieved. 30

The first effect of the work rolls is to rotate the work and progress it longitudinally through the pass which extends substantially the full length of the work rolls. At the circle of the 35 gorge or pass, the points of contact of the work rolls with the work are in the same straight line that passes through the axes of the two work rolls and consequently pressure of the rolls is applied perpendicularly to the surface of the work. This condition prevails only along the 40 line which is the intersection of the planes in which the respective gorge circles lie, this line being perpendicular to the longitudinal axis of the mill. In all other planes perpendicular to such axis the radii of the two work rolls at their 45 points of contact with the work are out of alignment with each other and with the line of pressure of the roll. In consequence of this condition, the effect of the pressure of the work roll on the work is reduced to that component thereof which acts on the work along the line which joins the axis of the roll to the point of tangency with the work. Thus the pressure of the work rolls on the work increases from a minimum at the entering end to a maximum at the 50 circle of the gorge or pass and then decreases gradually until the work is entirely clear of the 55 rolls.

In this operation, the work is gradually brought to correct size by pressure applied radially or transversely to the longitudinal axis. Consequently, the sizing is accurate and uniform throughout the length of the work and, as the work is not submitted to any considerable longitudinal tension, there is no tendency to in- 60

tensify any surface defects in the work. At the same time, the cross-rolling of the work has the effect of truing it or making it accurately circular within the limits of commercial tolerance. Additional passes will make the work truly circular.

It is noted that on account of the concave shape of the work roll, the peripheral speed thereof differs at different points. This results in causing the roll surface to slip across the surface of the work and the rubbing action thus brought about serves to efficiently polish the surface of the work. This rubbing action, along with the sizing and truing action are helpful in correcting minor kinks and slight longitudinal curvature although the machine is neither intended nor adapted to do the work of an ordinary straightening machine. On the other hand, it has no tendency to bend the work, as in the case of die-drawing, and to a considerable extent makes it practicable to dispense with a separate straightening operation as may be necessitated by die drawing.

My machine is of universal application in the sense that the same rolls can be adjusted for use on work of different diameters. For such adjustment, no change is made in the angularity of the rolls, as the proximate elements of the rolls are parallel for tubes and bars of all diameters. All that is required, in such adjustment for size, is to move the rolls to positions distant from the axis of the pass equal to the radius desired for the tube or bar. It is also useful on steels or other metals that are of too low tensile strength to permit of cold drawing. On account of applying the pressure to the work transversely to the axis thereof, without any longitudinal skin friction, there is a minimum of molecular or internal strain on the work with a minimum of structural differentiation between the core and surface portion thereof.

While I have hereinbefore described my machine as having a set of two work rolls, it is obvious that three or more work rolls may be used in one set, if the work is of large enough diameter to permit them to contact with the work without interference with one another. In such case, the rolls are arranged at equal distances apart and are otherwise disposed as in the case of the two-roll set.

While my mill is especially useful for sizing tubes, it has a tendency to increase the wall thickness thereof. I attribute this tendency to the fact that the lines of contact of the work rolls with the stock in the pass are of such great length as to oppose considerable resistance to elongation of the metal so that the metal is compelled to flow radially or transversely rather than longitudinally and the length of the tube is shortened accordingly. Thus the degree of thickening of the tube wall may be governed by increasing or decreasing the length of the straight line contact of the pass with the work so as to increase or decrease the resistance to the plastic flow of the metal of the work longitudinally of the pass. Likewise, the mill has a cold working effect on the work, that is it changes its physical characteristics. This cold working effect is subject to control.

While I have hereinbefore described my mill as applicable to sizing, truing and polishing cold bars and tubes, it may also be used for hot rolling bars and tubes. In such case, it is best to shorten the rolls so as to decrease their resistance to the plastic flow of the metal longitudinally. When,

however, it is desired to increase the wall thickness of the tubes, the rolls should be made long enough to create such resistance to the longitudinal flow of the metal as to induce radial or transverse flow thereof.

What I claim is:

1. A work roll whose work surface is a hyperboloid of revolution generated by a straight line in a plane parallel with the axis of the roll and intersecting an axial plane perpendicular to said first mentioned plane at an angle of from fifteen to twenty-five degrees, said surface being of the formula:

$$\frac{Y^2}{B} + \frac{Z^2}{B} - \frac{X^2}{A} = 1$$

15

wherein A and B are positive constants and X, Y and Z are the coordinates of points in the surface referred respectively to three axes, each of which intersects the other two at right angles.

2. A work roll whose surface is a hyperboloid of revolution with straight line elements, each element being in a plane parallel to the axis of said work roll and disposed at an angle of from fifteen to twenty-five degrees to the plane of the axis perpendicular to said first mentioned plane.

3. A machine for sizing, truing or polishing bars and tubes comprising a framework and work rolls rotatably mounted therein and arranged with their axes inclined equally and in opposite directions in planes parallel to each other and to the longitudinal axis of the machine, the surface of said rolls being hyperboloids of revolution of the formula:

$$\frac{Y^2}{B} + \frac{Z^2}{B} - \frac{X^2}{A} = 1$$

35

wherein A and B are positive constants and X, Y and Z are the coordinates of points in the surface referred respectively to three axes, each of which intersects the other two at right angles.

4. A machine of the kind described comprising elongated rotatably mounted work rolls and means for driving same, said work rolls being disposed with their axes in parallel planes but inclining in opposite directions, the surface of each work roll being a hyperboloid of revolution generated by a straight line in a plane parallel with the axis of the roll and intersecting an axial plane perpendicular to said first mentioned plane at an angle of from fifteen to twenty-five degrees and the inclination of the axes of the rolls being equal to said angle, whereby the distance between said rolls is uniform throughout the working length of the rolls.

5. A machine for sizing, truing or polishing bars and tubes comprising a framework and work rolls rotatably mounted therein and arranged alongside each other to form a longitudinal pass, each of said work rolls having a surface in the form of a hyperboloid of revolution, the surface of said rolls being hyperboloids of revolution of the formula:

$$\frac{Y^2}{B} + \frac{Z^2}{B} - \frac{X^2}{A} = 1$$

55

wherein A and B are positive constants and X, Y and Z are the coordinates of points in the surface referred respectively to three axes, each of which intersects the other two at right angles, said rolls having their axes in planes parallel to each other and to the longitudinal axis of the pass and tilted in opposite directions in their planes at an angle equal to the skew angle of the surface of the work roll.

6. In a machine of the kind described, the combination of rotatably mounted work rolls and

75

means for driving same, said rolls being disposed with their axes in substantially parallel planes but inclining in opposite directions, the surface of each work roll being a hyperboloid of revolution generated by a straight line in a plane parallel with the axis of the roll and intersecting an axial plane perpendicular to said first mentioned plane at an angle of from fifteen to twenty-five degrees and the inclination of the axes of the rolls being equal to said angle, whereby the distance between said rolls is uniform throughout the working length of the rolls.

7. A work roll for sizing, truing and polishing bars and tubes whose surface is a hyperboloid of revolution whose mathematical formula is

$$\frac{Y^2}{B} + \frac{Z^2}{B} - \frac{X^2}{A} = 1$$

wherein A and B are positive constants and X, Y and Z are the coordinates of points in the surface referred respectively to three axes, each of which intersects the other two at right angles.
